PORTRABLE TELEVISION RECEIVER

Richard E. Lee, Cazenovia, and Frank M. Grunwald,
North Syracuse, N.Y., assignors to General Electric
Company, a corporation of New York

Filed Mar. 31, 1966, Ser. No. 1,708

Term of patent 14 years

(Cl. D56—4)

FIG.1

FIG.2

FIG.3

FIG.4

FIG. 5

FIGURE 1 is a perspective view of a portable television receiver embodying our new design;

FIGURE 2 is a top plan view on a reduced scale;

FIGURE 3 is a front elevational view;

FIGURE 4 is a side elevational view, the opposite side being substantially a mirror image thereof; and

FIGURE 5 is a rear elevational view.

We claim:

The ornamental design for a portable television receiver, as shown and described.
